United States Patent Office

Des. 180,639
Patented July 16, 1957

180,639

HANDBAG

Marvin L. Blatt, Brooklyn, N. Y.

Application November 8, 1956, Serial No. 43,703

Term of patent 7 years

(Cl. D87—3)

Fig. 1

Fig. 2

I claim:

The ornamental design for a handbag, as shown.
